[57] **CLAIM**

The ornamental design for toy for an aquarium, as shown and described.

DESCRIPTION

The file of this patent contains at least one drawings executed in color. Copies of this patent with color drawings will be provided by the Patent and Trademark Office upon request and payment of the necessary fee.

FIG. 1 is a front view of a toy for an aquarium showing my new design;

FIG. 2 is a rear view thereof;

FIG. 3 is a top view thereof;

FIG. 4 is a left side view thereof with the trunk in open position;

FIG. 5 is a right view of FIG. 1; and,

FIG. 6 is a view of the end of the air hose seen in FIG. 1. The bottom of the design is plain and unornamented and forms no part of the claimed design.
